Primary Examiner—Raphael Barkai*(74) Attorney, Agent, or Firm*—Nelson Mullins Riley & Scarborough, L.L.P.(57) **CLAIM**

The ornamental design of a ratchet wrench body, substantially as shown and described.

DESCRIPTION

FIG. 1 is a perspective view of a ratchet wrench body embodying the design of the present invention, a ratchet mechanism and reversing lever being illustrated in phantom. FIG. 2 is a right side elevational view of the ratchet wrench body illustrated in FIG. 1.

FIG. 3 is a left side elevational view of the ratchet wrench body shown in FIG. 1.

FIG. 4 is a top view of the ratchet wrench body shown in FIG. 1.

FIG. 5 is a bottom view of the ratchet wrench body shown in FIG. 1.

FIG. 6 is a front side elevational view of the ratchet wrench body illustrated in FIG. 1; and,

FIG. 7 is a back side elevational view of the ratchet wrench body illustrated in FIG. 1.
